United States Patent Office

Des. 194,148
Patented Nov. 27, 1962

194,148

TILE OR SIMILAR ARTICLE

Philip M. Brody, 170 Boulevard, Scarsdale, and Frederic
H. Rahr, 1 East End Ave., New York, N.Y.

Filed May 24, 1961, Ser. No. 65,324

Term of patent 14 years

(Cl. D18—2)

Fig.1

Fig. 2

Fig.3

Fig.4

Fig.5

FIG. 1 is a face view of a tile showing our new design. FIG. 2 is a cross-section taken on line 2—2 of FIG. 1. FIGS. 3, 4 and 5 are modified forms of the tile shown in FIG. 1.

In the figures, the heavy and light stippled areas are printed areas of, respectively, darker and lighter solid colors.

We claim:

The ornamental design for a tile or similar article, as shown and described.
